(57) **CLAIM**

The ornamental design for a lighting fixture, as shown and described.

DESCRIPTION

FIG. 1 is a front elevational view of a light fixture showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is an enlarged bottom plan view of a portion 7 in FIG. 4;

FIG. 8 is an enlarged sectional view taken along line 8-8 in FIG. 7; and,

FIG. 9 is a bottom perspective view thereof.

The broken lines illustrate environmental structure and form no part of the claimed design.

The dash-dot-dash lines illustrate a boundary of the claimed design for those figures.
